ADJUSTABLE BIAS FOR ELECTRON BEAM APPARATUS

Willem F. Westendorp, Schenectady, N.Y., assignor to General Electric Company, a corporation of New York

Application October 24, 1956, Serial No. 618,139

6 Claims. (Cl. 315—14)

This invention relates to a network for producing a bias voltage for electron beam apparatus and more particularly to an adjustable network for producing a bias voltage waveform which is readily controllable as to relative duration and which is independent of the operating voltage and current of the electron beam apparatus to which it is applied.

This invention may be adapted in various forms for application generally to many devices employing a cyclically varying, input voltage. It is, however, especially suited for use with high-energy electron-beam apparatus of the resonance transformer type such as disclosed in my Patent 2,144,518, issued January 17, 1939. In such apparatus, an electron gun provides high energy electrons for a directed beam in response to a sinusoidal applied voltage. Electrons from the gun pass through a focusing electrode and are then accelerated by successively higher potentials applied to a plurality of accelerating electrodes arrayed along the beam path.

It is apparent that electrons accelerated from this form of equipment would have a wide range of energies including those associated with the relatively low-potential portions of the applied voltage and those associated with peak portions. Generally, the accelerating voltage has a substantially sine-wave form, and the electron energy distribution follows this same function. Such a wide velocity distribution renders focusing of the beam extremely difficult and detracts from the efficiency of the apparatus because the lower energy electrons do no useful work and give rise to deleterious heating effects.

My copending applications, Serial No. 518,199, filed June 27, 1955, now Patent No. 2,821,655, and Serial No. 595,504, filed July 2, 1956, now Patent No. 2,844,757, and assigned to the same assignee as this application, pertain to circuits for biasing electron beam apparatus to obtain a beam of electrons which is substantially mono-energetic. A peak voltage having proper phase, amplitude, and periodicity with respect to the accelerating voltage is applied as a bias to the control electrode so that electrons flow in the equipment only during a peak portion of the cycle of the applied accelerating voltage. Such circuits are eminently suited for application to X-ray equipment and to certain forms of high energy electron beam irradiation equipment. However, these circuits employ a reference for the bias voltage which is determined from a fractional portion of the operating potentials, so that the phasing of the bias circuit is dependent upon the load current of the apparatus. Further, it would be desirable to provide a bias circuit in which the relative duration of the bias potential with respect to the useful half cycle of the operating potential is readily controllable without necessitating complicated adjustment of established circuit parameters.

Therefore, it is an object of this invention to provide a circuit to produce for electron beam apparatus a bias voltage having a wave-form which is inherently phased correctly with respect to the cyclically varying operating

voltage of the equipment, and independent of the magnitude of this operating voltage.

A further object of the invention is to provide a bias circuit for electron beam apparatus to produce a bias voltage wave-form which is readily adjustable with respect to the relative duration of the bias voltage and the useful half cycle of the cyclically varying operating voltage.

According to the illustrated embodiment of this invention, a network is provided for biasing resonance transformer electron beam apparatus. The network comprises a full wave rectifier bridge in series with the operating voltage supply of the apparatus and responsive to the dielectric or charging current that flows between the high voltage components of the apparatus and ground.

15 The rectifier bridge is connected to energize in parallel a wave-form generating circuit and a reference voltage circuit which cooperate to produce a bias voltage wave-form adjustable as to duration and inherently phased correctly with respect to the operating voltage.

20 Features of the invention which are believed to be novel are pointed out with particularity in the appended claims. However, for a better understanding of the invention, together with further objects and advantages thereof, reference should be had to the following description taken in conjunction with the accompanying drawing, wherein:

Fig. 1 is a schematic representation of a resonance transformer electron beam apparatus embodying this invention, and

Fig. 2 illustrates wave-forms useful in explaining the characteristics of the apparatus of Fig. 1.

Referring now to Fig. 1, there is illustrated at 1 a resonant transformer X-ray apparatus. It is understood, however, that my invention may be advantageously applied to other apparatus wherein it is desirable to apply a biasing voltage in conjunction with a cyclically varying operating voltage. The biasing network of this invention is designated generally at 2. The X-ray apparatus 1 includes a metallic enclosure or shield 3 surrounding the elements of the apparatus and grounded as at 4. The electron gun 5 comprises a filament 6 continuously heated to provide an emission limited electron supply. Suitably mounted relative to the filament is a control or focusing electrode 7 for shaping the electron beam and arrayed along the path of the beam is a series of accelerating electrodes 8. Operating voltage for the X-ray apparatus is supplied from a low alternating voltage source 9 by means of a resonance transformer comprising a primary winding 10 and stacked and series-connected secondary coils 11. Between shield 1 and the apparatus there is interposed a hemispherical high voltage shield 12 which, in conjunction with the shield 3, provides an equivalent capacitance path to ground as indicated by the equivalent capacitance 13.

55 In operation, the transformer secondary winding 11 is resonant with the capacity to ground and produces potentials in the order of 1 million volts. This operation is described in detail in my aforementioned Patent 2,144,518. These potentials are applied to the accelerating electrodes 8 by means of conductors 14 from respective taps 15 on the coil stack 10 to apply in synchronism discretely increased accelerating voltages in sequence along the beam direction. The electron beam from the gun emerges from the apparatus through the tube 16 passing through window 17. The filament 6 is energized from a filament supply winding 11' on top of the transformer secondary 11.

65 It will be readily apparent that the beam energies will tend to vary from energies associated with the low potential portions of the sinusoidal accelerating voltage applied to electrodes 8 to those potentials associated with peak potentials. Since the low energy portions of the

beam may be absorbed in the window 17 causing deleterious heating effects and producing no useful result, it is desirable that the beam current flow only during the peak voltage portions of the operating cycle. Biasing network 2 is provided according to this invention to apply a negative potential to control electrode 7 to cut off the electron beam in synchronism with the sinusoidal operating voltage.

The biasing network 2 comprises a rectifier bridge 18 connected in series with the high voltage terminal of the transformer secondary 11 and the shield 12 to provide a full wave rectified current at output terminals 19 and 20 having the indicated polarity and dependent upon the charging current flowing through the distributed capacity 13. A reference voltage circuit 21 is connected between terminals 19 and 20 and includes a rectifier 22 or other asymmetrically conducting device in series with a capacitor 23 so that the capacitor is charged by the full wave rectified current from the rectifier bridge 18. A shunt resistor 24 in parallel with capacitor 23 provides a discharge leakage path for the capacitor to establish the steady-state voltage developed on the capacitor. Connected in parallel with the capacitor circuit and in parallel with terminals 19 and 20 is a reactor circuit 26 comprising an inductance 27 and a series resistor 28. The function of the reactor circuit is to establish a nearly constant direct current which circulates through the rectifier bridge 18 and the reactor circuit 26. The output voltage from the biasing network may be applied to the primary winding 29 of a step-up transformer 30, the secondary winding 31 of which is connected between the filament 6 and the control electrode 7. Since the output voltage of the biasing network supplied to the transformer primary winding 29 has a substantial direct current component, it is necessary to provide a blocking capacitor 34. It is also desirable to provide in the circuit of the secondary winding 31 a direct current voltage restoring circuit. This circuit may take the form of a capacitor 32 connected in series with the winding 31 and the unilaterally conductive device 33 connected across the winding 31 and capacitor 32 and poled in the proper direction so that it does not suppress the negative voltage peaks produced by the biasing circuit.

The biasing network of the present invention, as an important feature, provides a bias whose duration and phase are independent of the operating voltage and current of the tube involved and which is timed to provide for conduction during a limited portion of the time that the device may be conducting and located near the crest of the voltage applied to the beam-forming electrodes so that the beam is made up of electrons having relatively high and relatively uniform acceleration. The present circuit takes advantage of the high, relatively constant alternating current voltage that exists between the high voltage shield, usually employed as an enclosure for the high voltage apparatus for distributing and determining the voltage gradient between this apparatus, and the enclosing tank which is usually operated at ground. In an apparatus operated at a million volts, for example, a dielectric current, that is, the charging current for the distributed capacitance illustrated schematically at 13 between the shield 12 and the tank 3, may be in the order of 30 milliamperes. In the biasing network illustrated, this current is utilized to produce the desired hold-off bias and, as will become apparent, is ideally phased for this purpose with respect to the accelerating potential applied to the tube 5. The current is passed through the full wave rectifier bridge 18. The output of this bridge circuit causes a current to flow through the reactor circuit including reactor 27 and resistor 28. The alternating current impedance of reactor 27 is sufficiently large to suppress largely the alternating component in the reactor circuit and to establish a substantially constant current curve, indicated by I_L in Fig. 2(c). The total rectified current from the network 18

is illustrated by the curve i , Fig. 2(c). During that portion of the current cycle where this current i exceeds the current I_L , the excess current flows through the capacitor circuit including the rectifier 22 and capacitor 23. After capacitor 23 has been initially charged in a previous current cycle, this occurs at a predetermined voltage of capacitor 23 so that as the value of current i in Fig. 1(c) exceeds the value of current I_L , the voltage of capacitor 23 is impressed on the primary winding 29 of transformer 30 through the blocking capacitor 34 and thus establishes the value of the negative bias voltage E_g illustrated in Fig. 2(b). The output transformer 30 of the biasing circuit is a step-up transformer which also serves to isolate the bias voltage supply circuit from the focusing electrode 7. The transformer draws a small magnetizing current and the voltage wave shape in the primary winding circuit is essentially the same as that applied to the focusing electrode. Since the circuit including the distributed capacity 13 between the shield 12 and the enclosing tank 3 is essentially capacitive, the current i of Fig. 2(c) leads the voltage E_g impressed on the discharge device 5 by almost exactly 90° . This places the intervals between the negative peaks of voltage E_b symmetrically about the zero point of the capacitive current i and as readily observed from a comparison with Fig. 2(a) places these intervals about the maximum point of the accelerating voltage applied to the discharge device 5. Accordingly, the periods during which the negative bias is removed from the electrode 7 occur about the portions of the supply voltage near maximum amplitude. This is illustrated in Fig. 1(a) where the beam current I_b is illustrated as a current pulse located centrally with respect to the voltage maximum applied to the discharge device and having a duration equal to the interval between the negative bias pulses E_b . It will be apparent to those skilled in the art that beam current flows only during those half cycles of the impressed voltage during which the cathode is negative with respect to the electrode 16.

It is apparent that the value of the resistor 28 directly affects the magnitude of the current I_L that is reached before the rectifier 22 becomes conductive and the capacitor is again effectively placed in circuit to receive charging current through rectifier 22. It is also apparent that the resistor 24 has an effect since it determines the rate of discharge of the capacitor during the period that the rectifier 22 is nonconductive and so determines the actual charge on the capacitor just prior to the instant that conduction of device 22 starts. The periods during which the negative bias voltage is produced and the periods between these negative voltage pulses are therefore determined essentially entirely by the relative magnitudes of resistors 28 and 24. The magnitude of the voltage, during the negative pulses is dependent on the absolute magnitude of these resistors.

In the foregoing description and particularly in the curves of Fig. 2, the voltage and current waves have been illustrated as if there were zero change in current through the inductance and zero change in voltage on the capacitor 23. These are idealized conditions, but theoretical analysis and tests have indicated that these assumptions are justified. There is, of course, a small decrease in the current I_L during the intervals between the negative voltage pulses of curve E_g during which time the energy of the inductance tends to circulate current through the rectifier and a gradual increase in current through the inductance as the charge on the capacitor 23 is fully restored during the negative voltage pulses. The change in the voltage of the capacitor during the beginning of the voltage pulse depends to a considerable extent upon the magnitude of the resistor 24 and the amount that the voltage on the capacitor has decreased during the preceding period of nonconduction of the rectifier 22, that is, the period between the negative biasing voltage peaks. However, the sides or edges of these

negative voltage peaks are relatively steep and the effect on the phase of the negative voltage pulse is negligible.

From the foregoing description, it is apparent that the present invention makes unique use of an electrical quantity existing in the equipment, namely, the dielectric or charging current that flows from the high voltage apparatus through the shield to the grounded enclosure, as a means for providing a timed voltage pulse with respect to the accelerating voltage applied to the beam. By a relatively simple selection of resistance values in the inductive and capacitive branches of the biasing circuit, it is possible to adjust the duration of the period of conduction and this conduction period is essentially symmetrical with respect to the instant of the maximum amplitude of the applied voltage wave and is independent of the operating voltage and current of the discharge device. With the resistance 28 having a value of 8000 ohms and the resistance 24 having a value of 12,000 ohms the period of conduction of the tube 5 is of approximately 42 degrees duration and increases to approximately 66 when these resistances have values of 4000 ohms and 20,500 ohms, respectively. These values of resistances are chosen to give approximately the same values of the negative bias peaks E_g . It is these two resistance values which may be adjusted to give the desired duration of conduction while maintaining substantially constant magnitude of the bias voltage peaks. Accordingly, the present invention overcomes many of the disadvantages inherent in prior art biasing circuits and may be carried out with a small number of readily obtainable components.

While I have described a particular embodiment of my invention, it will be apparent to those skilled in the art that changes and modifications may be made without departing from my invention in its broader aspects and I aim, therefore, in the appended claims to cover all such changes and modifications as fall within the true spirit and scope of my invention.

What I claim as new and desire to secure by Letters Patent of the United States is:

1. A system for producing a biasing voltage for high voltage electron beam apparatus in timed relation to an alternating supply voltage for said electron beam apparatus, comprising a network connected to respond to the dielectric current flowing between the high voltage parts of said apparatus ground exteriorly of said electron beam apparatus, said network including means providing a reference voltage and means responsive to the magnitude of said dielectric current for energizing said beam apparatus from said reference voltage to prevent the flow of electron beam current for that portion of the dielectric current wave that exceeds a predetermined value.

2. A network for producing a biasing voltage for high voltage electron beam apparatus in timed relation to an alternating supply voltage for said electron beam apparatus comprising a biasing network connected to respond to the charging current flowing between said high voltage apparatus and a shield, said network comprising rectifier means for converting said charging current to unidirectional pulsating current, means energized from said rectifier means for establishing a substantially constant current of smaller magnitude than the amplitude of said pulsating current and means for maintaining said electron beam apparatus nonconducting during the interval that said pulsating current exceeds said substantially constant current.

3. A network for producing a biasing voltage for high voltage electron beam apparatus in timed relation to an alternating supply voltage for said electron beam apparatus comprising a biasing network connected to respond to the charging current flowing between said high

voltage apparatus and a shield, said network comprising rectifier means for converting said charging current to unidirectional pulsating current, circuit means including a series-connected resistance and inductance energized from said rectifier means for establishing a substantially constant current of smaller magnitude than the amplitude of said pulsating current and means for maintaining said electron beam apparatus nonconducting during the interval that said pulsating current exceeds said substantially constant current.

4. A network for producing a biasing voltage for high voltage electron beam apparatus in timed relation to an alternating supply voltage for said electron beam apparatus comprising a biasing network connected to respond to the charging current flowing between said high voltage apparatus and a shield, said network comprising rectifier means for converting said charging current to unidirectional pulsating current, first circuit means energized from said rectifier means for establishing a substantially constant current of smaller magnitude than the amplitude of said pulsating current and second circuit means including a unilaterally conducting device and a capacitor in series and in parallel with said first circuit means for maintaining said electron beam apparatus nonconducting during the interval that said pulsating current exceeds said substantially constant current, said second circuit means including a resistor providing a discharge path for said capacitor.

5. A network for producing a biasing voltage for high voltage electron beam apparatus in timed relation to an alternating supply voltage for said electron beam apparatus comprising a biasing network connected to respond to the charging current flowing between said high voltage apparatus and a surrounding shield, said network comprising rectifier means for converting said charging current to unidirectional pulsating current, means energized from said rectifier means for establishing a substantially constant current of smaller magnitude than the amplitude of said pulsating current including resistance means for determining the magnitude of said constant current, and means for maintaining said electron beam apparatus nonconducting during the interval that said pulsating current exceeds said substantially constant current.

6. A network for biasing resonance transformer electron beam apparatus, said network comprising a rectifier bridge circuit for connection in series with the resonance transformer of the apparatus to produce a full-wave rectified current through said network, a reactor circuit connected across said bridge and including an inductor and a first resistor in series to establish a direct current of substantially constant predetermined magnitude through said bridge and a reference voltage circuit connected in parallel with said reactor circuit and including a capacitor and a rectifier in series and a second resistor shunting said capacitor to maintain a charge on said capacitor and thereby produce a reference bias voltage for said apparatus, said capacitor being effectively connected to the output of said network through said rectifier when the current through said rectifier bridge exceeds said predetermined magnitude.
